UNITED STATES PATENT OFFICE.

GUSTAVE KRIEGER AND EMIL KRIEGER, OF BROOKLYN, NEW YORK.

SHOE.

1,217,463.

Specification of Letters Patent. Patented Feb. 27, 1917.

Application filed May 13, 1916. Serial No. 97,261.

To all whom it may concern:

Be it known that we, GUSTAVE KRIEGER and EMIL KRIEGER, both citizens of the United States, and both residents of Brooklyn, in the county of Kings and State of New York, have invented certain new and useful Improvements in Shoes, of which the following is a specification.

This invention relates to a shoe of novel construction, and more particularly to novel and efficient means of constructing, applying and fixing the position of the welt.

In the accompanying drawing:

Figure 1 is a perspective view of the shoe-
upper with the welt attached;

Fig. 2, a section on line 2—2 of Fig. 1;

Fig. 3, a bottom view with the upper
lasted;

Fig. 4, a section on line 4—4 Fig. 3;

Fig. 5, a detail of part of the welt;

Fig. 6, a detail of part of the wire;

Fig. 7, a bottom view of the shoe com-
plete, showing the sole partly broken away
and

Fig. 8, a cross section on line 8—8 Fig. 7,
showing the sole.

The shoe consists essentially, of an upper 10, to the forward portion of which is sewn a welt 11, said welt extending along the 20 vamp and partly along the quarters, and having its inner edge substantially flush with the lower edge of the upper. The welt is composed of a strip of leather having a longitudinal groove 12 on the side facing the upper, and a plurality of transverse slits 13, extending along its center or toe-portion. Through the welt and upper, there extend, a plurality of perforations 14 adapted for the reception of the looped portions 15 of a continuous wire 16, the spacing of the perforations corresponding to that of the loops. Each of the loops is twisted at its root as at 17 and all the loops are turned inwardly (Fig. 7) so as to lie in a common plane. Through the loops is threaded a common draw string 18, by means of which the welt and upper are permanently fixed in position. An insole 19 may be fitted into the upper above the welt, 50 while the sole 20, is secured to the welt, and

also to an inturned flange 21 back of the welt and extending along the heel portion of the quarters. After the sole has been applied, the welt may be trimmed off to any extent desired.

In manufacturing the shoe we sew the grooved and slitted welt to the outer face of the upper (Figs. 1 and 2). The welt together with the upper is perforated, the wire loops 15 are projected through the 60 perforations and are twisted. The upper is fitted on a last 22 upon the base of which an insole 19 may first be placed, and the welt as well as the flange 21 is turned inward to project over the edge of the insole (Fig. 65 3). The draw string 18 is threaded to an fro through the loops 15 to fix the welt in position, the loops are hammered down as they are successively engaged by the string, the sole 20 is applied, and is trimmed off 70 together with the welt, to finish the operation.

It will be seen that in a shoe constructed as described, the welt is secured only to the upper and to the sole, and not to the insole, 75 so that the latter is altogether dispensable for the building up of the shoe. In this way, the manufacture of the shoe is considerably simplified, more particularly as the difficult operation of sewing the welt 80 to the insole while the shoe is upon the last, is supplanted by the comparatively easy operation of drawing the string through the loops while the latter stand off from the last. So also, the shoe will be found to 85 possess great strength and to retain its shape for a long period of time.

We claim:

1. A shoe comprising an upper, a welt se-
cured thereto, a looped wire engaging the 90
welt and a draw string engaging the looped
wire to position said upper and welt.

2. A shoe comprising an upper, a slitted
and apertured welt secured thereto, a wire
having a plurality of loops that engage the 95
welt-apertures, and a string engaging the
loops to position said upper and welt.

3. A shoe comprising an upper, a welt
secured to the outer side of the upper along
the lower edge thereof, said upper and welt 100

being apertured, a wire having a plurality of inwardly turned loops that engage the upper and welt, and a string engaging the loops to position said upper and welt.

5. 4. The method of making a shoe which consists in securing a welt to an upper, forming perforations in the welt, passing

looped portions of a wire through said perforations, and drawing a string through the looped portions to turn said looped portions 15 inwardly to strain the upper over the last.
